UNITED STATES PATENT OFFICE

HOMER T. DARLINGTON, OF WEST CHESTER, PENNSYLVANIA, ASSIGNOR TO MARTIN B. SCHUSTER, TRUSTEE, OF JOLIET, ILLINOIS

PROCESS AND APPARATUS FOR CRACKING AND TREATING HYDROCARBONS

Original application filed April 25, 1927, Serial No. 186,463. Divided and this application filed February 5, 1931. Serial No. 513,731.

This application is a division of my application, Serial No. 186,463, filed April 25, 1927.

An object of this invention is to provide a process and apparatus for more completely and efficiently cracking into low-boiling point hydrocarbons, and otherwise making marketable products out of petroleum hydrocarbons of relatively high-boiling points.

In carrying out my invention, I take an oil, for instance, crude oil, after the gasoline has been removed by topping, or gas oil, and introduce and subject said oil in a pressure cracking still to a hundred or more pounds of pressure per square inch and to a temperature of 700° F. or more, whereby gasoline, kerosene, and other heavier distillates volatilize or form and then volatilize. The vapors are passed into a cooling chamber, for instance, a dephlegmator, which condenses as an intermediate product distillates heavier than gasoline. This intermediate product I pump through a separate continuous tube still using a higher pressure, and, if desired, a higher temperature than was used in the first cracking, and the intermediate product is thereby altered into gasoline and into substantially heavier and higher boiling point products which I call manufactured charging stock.

My invention comprises treating under cracking conditions of heat and superatmospheric pressure an oil of comparatively high boiling point, for instance, crude or gas oil, or other cracking stock for the production of gasoline and of other volatile products by cracking and the separation and withdrawal from the "first or lower pressure" part of the system of a portion of the residue of heavier hydrocarbons to mix with the herein referred to intermediate product, which is cracked at a higher pressure than used in the first part of the system. It also comprises the production of a manufactured charging stock from the cracking mixture, and forcing the remainder or all of the manufactured charging stock to the first or lower pressure part of the cracking system.

The invention will be more fully understood by reference to the accompanying draw-

ing which shows diagrammatically apparatus for carrying out the invention.

In the drawing, a coil or other like apparatus 1 of approved type operating under relatively low pressure, is provided with means for heating as the burner 1^a. This still is preferably provided with suitable means for mechanical circulation, such as the pump 10^a. The valves shown are too numerous to require indicating by number, particularly 60 as their operation is so simple as to be readily understood without explanation.

The element 2 is a reaction or treatment chamber of approved type in communication by means of a pipe 10 and pump 10^a with the heating coil 1 from which coil charging stock treated therein passes through the pipe 10^b to the reaction chamber 2 for further cracking and vaporization.

The element 3 is a dephlegmator cooled by 70 pipe line 26, and may be any approved means of cooling and wholly or partly separating intermediate products, as already defined; 4 is a condenser of any approved type, and 5 is a gasoline storage tank; 6 is a high 75 pressure still, or other like apparatus adapted for treating at higher temperature and pressure than that applied in the still 1; 7 is a secondary reaction chamber adapted to receive oil heated by the high pressure still 80 6; 8 is a storage tank for a product, and 9 is a means of separating water from the intermediate product removed from the dephlegmator 3. The functions of the various pipe lines shown are self-evident, the directions of flow of the oil therethrough, being indicated by the arrows. They are controlled by valves, as shown.

In practice, charging stock is continuously or intermittently added to the low pressure 90 still 1 by means of the pump 10^a which receives this stock from a suitable source of supply through the pipe 19^a, there treated under conditions of temperature and superatmospheric pressure conducive to cracking, 95 and withdrawn at cracking temperature and pressure through the pipe 10^b into the reaction chamber 2 in which further cracking may take place, and from which herein defined intermediate products and gasoline are 100

removed in vapor form through the pipe 11 to the dephlegmator 3. Gasoline passes thence, as a vapor, through the valve control pipe line 15 into a condenser 4, and is transferred through the pipe line 18 and stored in the tank 5.

Sufficient charging stock is introduced either continuously or intermittently, through pipe 19^a to maintain hydrocarbon in a liquid form in the reaction chamber at a predetermined level in the upper part of that chamber, leaving, however, space for the vapors that separate out of the liquid to accumulate.

From the reaction chamber 2 a portion of the non-volatilized oil may be removed by valve-controlled pipe line as 10, located as convenience dictates, and again forced by a pump as 10^a, or other suitable means, to the coil 1 for reheating and further treatment and/or a portion of said non-volatilized oil may be withdrawn entirely from the system through pipe 30, or it may be withdrawn and carried through a convenient valve-controlled pipe line 20 and delivered to a line 14, carrying intermediate product from the dephlegmator 3 and be intermingled with such intermediate product.

The intermediate product is removed from the dephlegmator 3 through pipes 13 and 16, either selectively—the heavier fractions through the pipe line 16, the valve 16^a being open, and the lighter fractions through the pipe line 13—or non-selectively, and, either with or without commingling with heavier oil withdrawn from the reaction chamber 2, through the pipe 20, is carried through the pipe line 14, forced by a pump 14^a, or other suitable means of propulsion into and through the high pressure still 6, and there heated by means of the burner 6^a. It then passes through valve-controlled line 6^b to the secondary reaction chamber 7, where cracking continues, the vapors passing over into the dephlegmator 3 through pipe 12.

A part of the intermediate product passing through the high pressure still 6 may, if desired, be passed through the valve-controlled pipe line 19 directly to the low pressure still 1 as intermediately manufactured stock. When passed into chamber 7 for treatment, it may be made into a final product, which in turn can be transferred by the valve-controlled pipe line 17 to the stock tank 8, and withdrawn by line 31 or 29, or the residue from the reaction chamber 7 may be returned through the pipe line 24 to the main pipe line 19 and thence passed through the coil 1. If desired, intermediate reflux products from the dephlegmator 3 may be withdrawn through the valve-controlled outlet 23, and they may be passed through the water separator 9.

Thus it will be seen, as a preferred method of operation, I have provided means whereby

original charging stock is heated in a low pressure still, the vapors of the heated stock passing to a dephlegmator 3 or reflux condenser which separates the gasoline from the heavier condensate, the latter then passing to a high pressure still 6 and reaction chamber 7 which are better adapted to crack the kerosene and gas oil forming the bulk of the reflux or intermediate stock than is the low pressure still 1 and reaction chamber 2. The residuum remaining in the reaction chamber 7 is a much heavier stock than that received by the still 6. This residuum will not crack well in the high pressure still 6, but I have discovered that it does crack well in the low pressure still 1. I, therefore, return this manufactured charging stock to the still 1, and by pipe line 20 mix oil from still 1 with reflux from line 14 passing to the higher pressure still 6.

I have shown pressure gauges 32^a, 32^b, 32^c, 32^d, 32^e for indicating pressures; 33^a, 33^b, 33^c are means of indicating liquid levels, and 34^a, 34^b, 34^c, 34^d are means of determining temperatures.

While I have shown and described but a few embodiments of my invention, it is to be understood that it is capable of many modifications. Changes, therefore, in the construction and arrangement may be made which do not depart from the spirit and scope of the invention as disclosed in the appended claims.

I claim:

1. Apparatus for cracking hydrocarbon oil comprising a low-pressure heating coil, a reaction chamber in communication therewith, a fractionating condenser connected to and adapted to condense vapors from said reaction chamber, a high-pressure heating coil connected to and adapted to receive the heavier hydrocarbon fractions from said condenser, a secondary reaction chamber in communication with said high-pressure heating coil adapted to deliver vapors to a vapor condensing means, and means for passing portions of the unvaporized oil from the secondary reaction chamber to the low-pressure heating coil.

2. Apparatus for treating hydrocarbon oil comprising a low-pressure heating coil, a reaction chamber in communication therewith, a fractional condenser adapted to condense vapors from said reaction chamber, a high-pressure heating coil adapted to receive the heavier hydrocarbon fractions from said condenser, a secondary reaction chamber in communication with said high-pressure heating coil adapted to deliver vapors to a vapor condensing means, means for passing portions of the unvaporized oil from the secondary reaction chamber to the low-pressure heating coil, means for withdrawing gasoline, means for withdrawing an unvaporized

product, and a means for supplying fresh charging stock to the apparatus.

3. Apparatus for cracking hydrocarbon oils to make gasoline comprising low-pressure means for heating and cracking said oils, a fractionating condenser receiving vapors from said heating means, means for condensing vapors of gasoline, a high-pressure heating means including a reaction chamber, means for feeding condensate heavier than gasoline from said fractionating condenser to said high-pressure heating means, means for conveying vapors from said reaction chamber to said fractionating condenser, means for passing unvaporized stock from said reaction chamber to said low-pressure heating means, means for withdrawing gasoline, means for withdrawing a manufactured unvaporized product, and means for supplying fresh charging stock to the apparatus.

4. The process of cracking hydrocarbon oils to produce gasoline comprising heating the hydrocarbon oils under low pressure conditions, fractionally condensing the vapors produced by said heating, withdrawing a condensed intermediate product heavier than gasoline from the fractional condensing stage, heating and cracking said intermediate product under high-pressure conditions, condensing the vapors produced by the high-pressure heating, passing unvaporized stock from the high-pressure heating to the starting point where low pressure heating again occurs, and continuously withdrawing unvolatilized liquid oil from the lower pressure cracking means and uniting it with said condensed intermediate product which is passing to said high-pressure cracking stage.

5. The process of cracking hydrocarbon oils to produce gasoline comprising heating the hydrocarbon oils under low pressure conditions, fractionally condensing the vapors produced by said heating, withdrawing fractions heavier than gasoline, heating and cracking said fractions under high-pressure conditions, condensing the vapors produced by the high-pressure heating, passing unvaporized stock from the high-pressure heating to the starting point where low-pressure heating again occurs, continuously withdrawing unvolatilized liquid oil from the lower pressure cracking stage, and passing said oil to the high-pressure cracking stage.

6. The process of cracking hydrocarbon oils to produce gasoline comprising primarily heating the hydrocarbon oils under superatmospheric pressure, fractionally condensing the vapors produced by said first heating, withdrawing a condensed intermediate product heavier than gasoline from the fractional condensing stage, heating and cracking said intermediate product in a second zone, condensing the vapors produced by said second heating, passing unvaporized stock from the

second heating to the starting point where the first heating again occurs, and continuously withdrawing unvolatilized liquid oil from the first cracking stage and uniting it with said condensed intermediate product which is passing to said second cracking stage.

7. Apparatus for cracking hydrocarbon oils comprising a low-pressure still, a high-pressure still, means individual to each still for separating vapors from unvaporized stock, means for fractionally condensing oil vapors from said stills, means for withdrawing a condensed intermediate product heavier than gasoline from the fractional condensing means, means for passing unvaporized stock from the high-pressure still to the low-pressure still, means for continuously withdrawing unvolatilized liquid oil from the low-pressure still and for uniting it with said intermediate product, and means for pumping said mixture to the high-pressure still.

8. Apparatus for cracking hydrocarbon oils comprising a low-pressure still, a high-pressure still, means individual to each still for separating vapors from unvaporized stock, means for fractionally condensing oil vapors from said stills, means for withdrawing a condensed intermediate product heavier than gasoline from the fractional condensing means, means for passing unvaporized stock from the high-pressure still to the low-pressure still, and means for passing unvolatilized oil from the low-pressure still to the high-pressure still.

9. The process of treating hydrocarbons as described in claim 4 characterized by continually adding fresh hydrocarbons to maintain a predetermined amount of liquid throughout the system, continually removing a portion of the unvaporized hydrocarbons from the system, and continually removing gasoline from the system.

10. The process of treating hydrocarbons as described in claim 5 characterized by continually adding fresh hydrocarbons to maintain a predetermined amount of liquid throughout the system, continually removing a portion of the unvaporized hydrocarbons from the system, and continually removing gasoline from the system.

11. The process of cracking hydrocarbon oils which consists in heating and cracking an oil stock heavier than kerosene, separating vaporized products therefrom in a separating zone, partially condensing the vaporized products to produce a condensate heavier than gasoline and lighter than the feed stock and including substantial amounts of kerosene constituents, heating and cracking a substantial portion of the condensate in a separate operation under conditions of temperature and pressure suitable for cracking kerosene constituents, separating vaporized material therefrom in a second separating zone, and returning unvaporized residual material

heavier than the condensate and lighter than the original oil stock from the second separating zone to the first cracking operation.

12. The process of cracking hydrocarbon oils which consists in subjecting said oils to cracking conditions in a low-pressure zone, separating vaporized products therefrom, partially condensing said vaporized products, subjecting said condensate together with unvaporized oil continuously withdrawn from the low-pressure cracking operation to cracking conditions in a separate operation in a high-pressure zone, and returning unvaporized residue from the high-pressure zone to the low-pressure zone.

13. The process of cracking hydrocarbon oils which consists in circulating said oil through a low-pressure heating and cracking zone, withdrawing vapors formed therein, partially condensing said vapors, subjecting the condensate together with oil unvaporized in said zone to cracking conditions in a separate zone operating at a higher pressure than the first zone, separately removing vapors from the residue in said separate zone, and returning unvaporized residue from the separate zone to the first zone.
